UNITED STATES PATENT OFFICE.

FRANK C. WIDMANN, OF CLEVELAND, OHIO.

RING-MOLD.

1,000,470.

Specification of Letters Patent. Patented Aug. 15, 1911.

Application filed February 11, 1908. Serial No. 415,340.

To all whom it may concern:

Be it known that I, FRANK C. WIDMANN, a citizen of the United States, residing at Cleveland, in the county of Cuyahoga and 5 State of Ohio, have invented a certain new and useful Improvement in Ring-Molds, of which the following is a full, clear, and exact description, reference being had to the accompanying drawings.

10 This invention relates to molds such as used by jewelers for casting rings. In my Patent No. 844,072 issued February 12th, 1907, there is shown a mold for this purpose which comprises two mold sections, 15 each of which is made of iron, with an integral central core of similar material which is adapted to be assembled with said sections to produce a complete mold. This mold has proven satisfactory and efficient in 20 operation, provided that the mold is heated before pouring the molten gold thereinto. It will not work satisfactorily, however, unless so heated prior to the pouring of the molten gold thereinto, the gold refusing to 25 flow readily on the cold iron surfaces of the mold. Furthermore, the iron has to be specially prepared to prevent the adherence of gold thereto even after it has been heated,—such special preparation consisting 30 generally in burning the iron with horse-hoof.

The object of this invention is to provide a mold whereinto the gold may be poured without the necessity for preheating 35 the mold and without liability to crack the band or produce cavities therein.

A further object of the invention is to accomplish the above results in a mold which is simple of construction and cheap of production.

I accomplish these objects by the embodiment of my invention illustrated in the drawings forming part hereof, wherein—

Figure 1 represents a perspective view of 45 the complete mold, showing the same opened up with the center and head cores in place; Fig. 2 represents a side elevation of the assembled mold; Fig. 3 represents an elevation of one of the mold sections with the cores in 50 place, the center core being represented in

section; and Fig. 4 represents an enlarged sectional view of the head core and of the adjacent portions of the ring.

Describing the parts by reference characters, 1 and 2 denote the body portions or 55 sections of the mold. These sections may be formed as rectangular blocks, and each is provided with a central aperture 3 extending therethrough. Surrounding the central aperture in each block is an incomplete or 60 fractional annular groove 4, whereby, when said sections are assembled, a complete mold groove is provided for the body or band of the ring. Each fractional groove may be provided with a suitable number of frac- 65 tional vents 5 formed in the inner faces of the sections 1 and 2 and extending to the sides thereof, placing the mold groove in communication with the atmosphere. Four such vent passages are shown, the frac- 70 tional passages in one member matching or registering with those in the other whereby, when the sections are assembled, four complete vent passages are provided, extending from the mold groove to the outside of the 75 mold. Two of these vent passages communicate with the upper portion of the ring mold groove and extend thence upwardly to the outer surface of the mold, and the remaining two communicate with the lower 80 portion of the ring mold groove and extend downwardly to the exterior of the mold.

Mold section 2 is provided with dowel pins 6 and section 1 with holes 7 so located as to cause the sections to be assembled with 85 the groove sections 4 and vent passages in the two sections in direct opposition to each other. Each section 1 and 2 is provided with a fractional inlet groove 9 communicat- 90 ing with its fractional mold groove, said inlet grooves forming, when the sections are assembled, a hopper-like inlet for pouring the molten gold into the mold. Each section 1 and 2 is also provided in the lower portion thereof with a fractional groove 11 95 extending from the lower surface of the section to the lower portion of the fractional ring mold groove. These grooves are of such shape that, when the sections are assembled, a passageway is provided which is 100

adapted to receive and closely surround the core 12 by which the ring head is formed. To secure the parts of the mold together, each section is provided with a hook 13 and 5 a stud 14, whereby the parts may be held in operative relation during the operation of casting.

Core 12 is preferably an integral body having a stem 15 adapted to project beyond 10 the lower portion of the mold and a contracted body portion 16, the lower portion of which is substantially cylindrical and the upper portion of which is preferably frusto-conical. The frusto-conical surface is provided with grooves 18, said grooves diminishing in cross-sectional area from top to bottom thereof to form correspondingly shaped claws or arms for the setting. The lower end of each of these grooves 15 communicates with a vent passage 19 extending the 20 length of the contracted cylindrical portion 16 of the core and communicating with the exterior of the mold. The provision of the vent grooves 5 and 18 contributes to the 25 formation of a perfect casting, which result is further facilitated by other features of the mold to be discussed hereinafter. The core 12 is supported within the mold by means of a pin 20 extending through an aperture in 30 the core and through corresponding apertures 21 in the core sections.

For the material of which the mold sections are composed, I employ a metal to which the molten gold will not adhere when 35 said metal is cold. I have found aluminum to be particularly well suited for this purpose, as it requires no special preparation, such as has been mentioned in connection with iron molds. In attempting to make 40 rings by pouring the molten gold into a cold aluminum mold constructed with a central integral core within each groove 4, it has been found that the contraction of the gold in cooling against the solid core thus 45 provided causes the band to break, generally at two portions located on opposite sides of the inlet groove 9. To overcome this objection, I provide a central core 22 of material which will not resist the contraction of the 50 gold in cooling to such extent as to fracture the band. I have found cuttlefish and charcoal to be admirably adapted for this purpose, as they are porous and are charred or burned by the molten gold sufficiently to accommodate the contraction thereof in cooling, 55 at the same time forming a firm support for the inner surface of the band. It frequently happens, however, that bands thus produced have cavities on the inner faces 60 thereof adjacent to the core. To prevent the formation of such cavities, I provide the core 22 with ports so arranged as to distribute some of the molten gold directly to the interior of the groove 4. For this pur-

pose, I provide the core 22 with a vertical 65 port 23 extending from the upper surface substantially to the center thereof, where it merges with a pair of downwardly inclined ports 24 and 25 leading to opposite portions of the groove 4 and discharging into said 70 groove at points substantially equidistant from the inlet port. I have found that good results are obtained by making the diameters of these ports equal to about one-half or one-third of the width of the groove 4. To center the core 22 properly with reference to the groove and to the inlet port 9, I provide the core 12 with a pin 26, which not only extends through the ring groove to form the opening through the body of the ring 75 behind the setting but extends into a corresponding opening 27 in core 22, said opening being arranged substantially midway between the outlet ends of ports 24 and 25, and said recess and ports 23, 24 and 25 being 80 in the same plane. The pin 26 is preferably made of steel or iron; for, should it be formed of aluminum (as is the case with core 12), it would be melted by the molten 85 gold. 90

It will be observed that the upper ends of the mold sections are provided respectively with plates 28 and 29 which are secured thereto and are provided each with a fractional aperture constituting the inlet 95 through which molten metal is introduced into the port 9. These plates are preferably of steel and are secured to the aluminum body beneath by means of screws 30. The purpose of these plates is to protect the 100 aluminum of which the mold body is composed from being melted by the contact therewith of the crucible from which the molten gold is introduced into the mold. The length of time that the crucible usually 105 rests upon the top of the mold in pouring will be sufficient to melt the aluminum body molds, and the plates 28 and 29 prevent this action.

Before assembling the parts, I apply 110 lycopodium powder to the central core 22 and to the inner faces of the mold sections and apply oil to the core 12.

By the construction described, I have produced a mold which is simple of construction, cheap of production, but which will enable substantially perfect rings to be cast without the necessity for heating the mold body, and which can be used repeatedly 115 without deterioration,—the only part subject to renewal being the core 22. As this core may be made of charcoal, the cost of renewal is practically negligible.

Having thus described my invention, I 120 claim:

1. A ring mold comprising a pair of sections of aluminum each having therein a fractional groove, means for securing said

sections together, a core coöperating with the ring groove and formed of a material which will accommodate the contraction of the gold in cooling, said core having 5 ports for receiving molten metal and distributing the same to various parts of the mold groove.

2. A ring mold comprising a body of metal to which molten gold will not adhere 10 when said metal is unheated, said body having a mold groove therein, and a core within said groove, said core being formed of material which will accommodate the contraction of the gold in cooling and having ports 15 for receiving molten gold and distributing the same to the interior of the mold groove.

3. A ring mold having an inlet port and comprising a pair of sections made of metal to which molten gold will not adhere when 20 said metal is unheated, said sections having each a fractional mold groove therein and a core removably fitted within said groove, said core consisting of a body having therein a vertical port adapted to communicate 25 with the inlet port of the mold and provided with lateral ports communicating with said vertical port and extending through said core to opposite portions of the mold groove.

30 4. A ring mold comprising a pair of symmetrical sections made of metal to which molten gold will not adhere when said metal is unheated, each section having therein a fractional inlet port and a fractional mold 35 groove, a core located within said groove, said core consisting of a body having therein a vertical port adapted to communicate with the inlet port of the mold and with downwardly extending lateral ports communicating with said vertical port and extending through said core to opposite portions of the mold groove.

5. In a ring mold, the combination of a body having an inlet port and having there- 45 in a mold groove for the body or band of the ring and a transverse aperture within said groove, a core removably fitted in said aperture and having a port adapted to communicate with the inlet port of the body 50 and one or more distributing ports leading from the former port to the mold groove, and a core removably fitted in said body and having a centering projection adapted to engage the former core.

55 6. In a ring mold, the combination, with a body having therein a mold groove for the body or band of the ring and an inlet port extending into said groove, a transverse aperture within said groove and a second 60 aperture for the reception of the ring-head core, of a core fitted in the former aperture and having a receiving port adapted to communicate with the inlet port and with distributing ports extending from the former

port and also having a recess intermediate 65 between the discharge ends of the distributing ports, and a ring-head core having a projection adapted to extend into the aperture in the former core and thereby center 70 the same.

7. In a ring mold, the combination of a pair of sections each having a fractional mold groove therein and a fractional inlet port communicating with its fractional groove, each section having a groove for the 75 reception of the ring-head core and a transverse aperture within the mold groove, a core in said transverse aperture provided with a port adapted to communicate with the inlet port and with branch distributing 80 ports extending from the receiving port through opposite portions of the core, and a ring-head core in the groove therefor, the latter core being provided with means for 85 centering the former core.

8. In a ring mold, the combination of an aluminum body having therein a mold groove and an inlet port communicating with said groove, said body being provided with an aperture extending transversely of 90 and located within the mold groove, and a core of material, as charcoal, in said aperture, said core having an inlet port adapted to communicate with the inlet port of the body and with one or more distributing 95 ports communicating with the mold groove.

9. In a ring mold, the combination, with an aluminum body having therein a mold groove, an inlet port communicating with said groove, a groove for the reception of the 100 head core, and an aperture extending transversely of the mold groove and within said groove, of a core of material, as charcoal, located in said transverse aperture and having receiving and distributing ports adapted 105 to distribute molten metal from the inlet port to opposite portions of the mold groove, and an aluminum ring-head core in its groove provided with a projection of relatively non-fusible material adapted to 110 engage the former core to center the same.

10. In a ring mold, the combination, with a body of metal to which, when unheated, molten metal will not adhere, said body having therein a mold groove, a groove for the 115 reception of the head core and an aperture extending transversely of the mold groove and within said groove, of a core located in said transverse aperture and having receiving and distributing ports adapted to distribute molten metal from the inlet port to opposite portions of the mold groove, and a ring-head core of metal to which, when unheated, the molten gold will not adhere, the latter core being provided with a projection of relatively non-fusible metal adapted 120 to engage the former core to center the same.

11. A ring mold comprising a pair of symmetrical sections made of aluminum, each section having a fractional mold groove therein and a fractional inlet port communicating with the fractional mold groove, and a plate of relatively non-fusible metal applied to the inlet end of each of said sections and having a fractional aper-

ture communicating with the fractional inlet port.

In testimony whereof, I hereunto affix my signature in the presence of two witnesses.

FRANK C. WIDMANN.
